UNITED STATES PATENT OFFICE

94,778

DESIGN FOR A CHAIR

Enrique A. Rавентос, Chicago, Ill., assignor to Marshall Field & Company, Chicago, Ill., a corporation of Illinois

Application January 4, 1935, Serial No. 54,722

Term of patent 7 years

To all whom it may concern:

Be it known that I, Enrique A. Rавентос, a citizen of the United States, residing at Chicago, in the county of Cook and State of Illinois, have invented a new, original, and ornamental Design for a Chair, of which the following is a specification, reference being had to the accompanying drawing, forming a part thereof, in which the figure is a perspective view of a chair embodying my new design.

I claim:

The ornamental design for a chair as shown.

ENRIQUE A. RAVENTOS.
